ELECTRICAL CONNECTOR

Filed March 9, 1936

UNITED STATES PATENT OFFICE

2,179,636

ELECTRICAL CONNECTOR

Charles H. Koehler, Oak Park, Ill.

Application March 9, 1936, Serial No. 67,849

8 Claims. (Cl. 200—163)

This invention relates to electrical connectors, and more particularly is directed to such connectors for establishing connection between two fixed terminal members by means of an intermediate connecting member having relative movement with respect to the terminal members.

The present invention is a continuation in part of my copending application, Serial No. 30,283, filed July 8, 1935, now Patent No. 2,123,631, patented July 12, 1938, and is concerned with the provision of a switching member capable of maintaining substantially uniform equalized contact pressure between the terminal members and the connector irrespective of limited misalignment between the terminal members.

One of the primary objects of the present invention is the provision of means for readily connecting and disconnecting equipment such as switches, circuit breakers, connectors and the like, in their respective circuits, with compensation for axial and other misalignment of the parts, while assuring maintenance of equalized contact pressure of ample unvarying contact area in all positions of such misalignment.

In its preferred embodiment, the present invention contemplates a means for connecting two fixed contact terminals with a floating self-aligning connector, mechanically or manually moved into and out of operative position.

One of the objects of the present invention is to provide a means for connecting the studs of a circuit breaker or the like with the associated stationary contacts, by means of a floating-self-aligning connector which maintains, in all allowable positions of misalignment, an equalized contact pressure of unvarying contact area.

Another object of the present invention is to provide a substantially resilient contact engagement between the connector member and the terminal member by forming one of the members of a plurality of contact shoes which are pressed into equalized engagement with the other member regardless of the angular misalignment therebetween, and which provide a substantially uniform contact area in all positions of engagement.

Still another object of the present invention is the elimination of spring means from any part of the electrical circuit through the terminals, whereby the life of the springs is materially increased.

In the provision of a disconnecting device or connector for connecting and disconnecting two spaced terminals, special requirements usually demand a compact but sturdy construction. The present invention finds particular application for

such use and produces a high grade efficient contact device. Also, because of its self-aligning characteristics, the present invention is capable of being employed in connection with the terminals of circuit breakers, if desired, since the 5 sockets or terminals of such breakers must be self-adjusting and capable of maintaining equalized contact pressure upon the male contact plugs with which the breaker terminals are engaged when the breaker is connected in switch- 10 closed position. It is to be understood, however, that the invention is not to be limited to these specific uses, since the broad features thereof are applicable in various other fields.

Other objects and advantages of the present 15 invention will appear more fully from the following detailed description which, taken in conjunction with the accompanying drawing, will disclose to those skilled in the art the particular construction and operation of a preferred form of 20 the present invention.

In the drawing:

Figure 1 is a vertical sectional view through one form of switch connection embodying the principles of the present invention;

Figure 2 is a corresponding vertical sectional view of a second form of the invention;

Figure 3 is a sectional view taken substantially on line 3—3 of Figure 2;

Figure 4 is a sectional view taken substantially on line 4—4 of Figure 2;

Figure 5 is a sectional view corresponding to Figure 3, showing a modified form of spider construction; and

Figure 6 is a sectional view taken substantially on line 6—6 of Figure 5.

Referring now in detail to the structure shown in Figure 1, I have disclosed a form of connection in which only two areas of contact are required to effect electrical connection between a 40 pair of spaced contacts.

In this construction, I provide a fixed contact member 10, having a normally extending arm 12 supported on a suitable supporting bracket 13. The contact member 10 is provided with a ball tip end 14, and is also provided with a longitudinally extending central passageway 15 receiving the internally threaded sleeve 16 which is mounted therein and which is adapted to receive the threaded shaft 17 projecting therethrough. The 45 sleeve 16 has an extending portion projecting below the contact 10 and carrying the bevel gear member 18 keyed thereto. The gear 18 is driven by a second gear member 19 supported on a driving shaft 20.

The threaded shaft 17 is adapted to reciprocate within the passageway 15 upon rotation of the gear 18, the shaft 17 having a suitable stop member 22 limiting its downward movement within the passageway 15. The stop 22 slides in a suitable keyway 23 formed in the passageway 15 to prevent rotation of the shaft 17 and to provide for only longitudinal movement thereof. The upper end of shaft 17 has a socket 21 receiving the ball end of a pin 24 mounted for universal movement about the upper end of the shaft 17.

At its upper end, the pin 24 is provided with the spider member 25 having radially extending arms 26 passing through suitable openings formed in a plurality of contact shoe members or bars 27, the outer lateral surface of the contact bars 27 being provided with tapered recesses 28 receiving the helically coiled spring members 29 carried by the arms 26 and biased at their outer ends against a stop plate 30 secured to the outer ends of the arms. This provides for resilient movement of the contact bars 27 inwardly and outwardly with respect to the spider 25, and also provides for resilient and uniform equalized contact pressure of the bars against the ball tip end 31 of a contact member 32 fixed at a predetermined distance from the contact 10.

The lower ends of the contact bars 27 are also provided with tapered recesses 33 formed in the outer lateral surfaces thereof, which recesses are adapted to receive helically coiled springs 34 normally biasing the lower ends of the contact bars into contact engagement with the ball tip 14 of the contact 10. The springs are maintained in proper biasing position by an encircling housing member 35 having suitable inset portions 36 forming spring seats for the springs 34. In this manner the lower ends of the contact bars 27 are biased inwardly into uniform equalized contact pressure of unvarying area with the lateral surface of the ball tip 14. Preferably, the inner contacting surfaces of the contact bars 27 and the ball tips 14 and 31 of the contacts 10 and 32 are silver plated in order to reduce the resistance to passage of current therethrough.

In the operation of the structure shown in Figure 1, in the position shown in this figure the contact bars 27 have been moved upwardly to provide for contacting engagement between the contacts 10 and 32. When it is desired to disconnect the electrical connection between these contacts, the shaft 20 is rotated by any suitable driving means to effect corresponding rotation of the sleeve 16. This results in threading of the shaft 17 downwardly within the passage 15, and results in corresponding movement of the contact bars 27 due to their engagement by the arms 26 of the spider 25 secured on the sleeve member, away from the ball tip 31, disconnecting the contact 10 therefrom. At the same time, the lower ends of the contact bars are moved downwardly past the ball tip 14 of the contact 10 until the contact bars 27 assume a position with the spider 25 disposed immediately above the ball contact tip 14 of the contact 10, with the lower ends of the contact bars 27 being disposed about the lower cylindrical portion of the contact 10.

This provides a suitable clearance between the contacts 10 and 32, and at the same time produces wiping engagement of the inner surfaces of the contact bars 27 across the ball contact tip 14, and also across the ball contact tip 31 when the bars are moved upwardly into contact engag-

ing position. This is advantageous in providing clean and positive contact between the contact tips and the contact bars, thus reducing the resistance through the connection. At the same time, the spring mounting of the contact bars 27 at their upper and lower ends assures that equalized contact pressure of unvarying uniform area will be provided between the contact tips 14 and 31 and the portion of the bars in engagement therewith.

Obviously, the reciprocatory movement of the contact bars 27 might be secured by other means than the threaded shaft fitting into the sleeve 16, and I do not intend to limit my invention to this specific form of actuating mechanism, since a suitable plunger member might be employed for producing the same mode of operation. Further, even if a slight misalignment of the contacts 32 and 10 is present, the resilient mounting of the contact bars 27 upon the sleeve or pin 24 insures that such misalignment will be accommodated, and that equalized contact pressure will be produced regardless of such misalignment.

Considering now in detail the embodiment of the invention shown in Figures 2 to 4, inclusive, a contact stud 40 is provided with an extending threaded portion 42 receiving a support member 43 threaded thereover and having a laterally extending portion 44 which receives a hollow metallic tube 45 threaded into a recess formed in the portion 44 of the member 43.

Within the lower end of the tube 45 there is provided a bushing 46 which has an annular shoulder 47 seating on the bottom of the recess into which the tube 45 extends. The bushing 46 also has an extending cylindrical portion 48 which extends into a suitable recess formed in the member 44, the bushing serving as a guide for the lower end 49 of a threaded shaft 50, which shaft at its lower end is provided with a helical gear 52 having bearing support within a suitable supporting bracket member 53. Suitable thrust washers 54 are provided at opposite ends of the gear 52, and the gear is adapted to be rotated by a second helical gear 55 carried within suitable bushings 56 extending into opposite ends of a cylindrical recess formed in the member 53. Suitable graphite or other bearing members 57 are interposed between the ends of the gear 55 and the bushing 56, the bushing 56 being bolted into position by means of the stud bolts 58 threading into the lateral walls of the bracket 53.

The bracket 53 is also provided with oppositely extending flanged shoulders 59, which shoulders are adapted to receive suitable stud members 60 securing the bracket 53 to the portion 44 of the member 43. It will be noted that the bracket 53 may be rotated through a limited arc with respect to the member 44 in order to provide for variation in alignment between the member 44 and the shaft 62 which carries the gear 55.

The shaft 62 extends outwardly of the bushing 56 and is provided with squared end portions 63, one of the end portions 63 receiving a crank member 64 whereby the shaft 62 may be rotated in opposite directions to produce corresponding rotation of the threaded shaft 50.

The upper end of the tubular member 45 is provided with a relatively spherical external bead 65, which bead is adapted to form a suitable contact surface engaged by a plurality of contact shoes 66 having the arcuate inner surfaces thereof engaging about the bead 65 at the lower end thereof. The contact shoes 66 are also provided with concave recesses 67 accommodating 75

the universal movement of the assembly as it moves toward contact engaging position. A plurality of spring members of cupped cross section, indicated at 68, are adapted to engage in suitably notched portions of the external surface of the members 66, being held in position by means of a polygonal band 69 surrounding the shoes and connected with the spring 68 by means of the adjustable threaded pin members 70 which have suitable seating engagement in the arched portions of the spring 68. This serves to urge the shoes 66 resiliently into engagement with the upper end of the tubular member 45 and to maintain equalized pressure between each of the shoes 15 and the contact surface 65 of the member 45.

The threaded shaft 50 is provided with a spherical traveling nut 72 adapted to move upwardly and downwardly on the shaft 50 by means of the pin 73 guided in the keyway 74 formed in the internal surface of the member 45, whereby the nut 72 is prevented from rotation and threads upwardly and downwardly upon the shaft 50 as the shaft is rotated.

A suitable supporting sleeve 75 is provided at its lower end with a socket portion 76 welded or otherwise suitably secured thereto which engages about the spherical surface of the traveling nut 72 to provide for substantially universal movement of the sleeve 75 about the member 72. The beaded contact surface 65 has a center of curvature disposed at a point common to the center of the ball nut 72 and the center of the internal surface of the socket portion 76. The socket portion 76 of the member 75 is suitably milled out as shown at 77 about the pin 73 to provide for this universal movement of the sleeve 75 about the traveling nut.

The upper end of the sleeve 75 is provided with an annular disc-like member or spider 80 having a plurality of radially extending slots milled into the outer surface thereof, which slots are adapted to receive radially extending blade or cam members 82, the members 82 extending radially outwardly of the spider 80 and being suitably welded or otherwise secured in the milled out slots formed in the outer surface of the spider 80. The upper ends of the shoe members 66 are slotted, as indicated at 83, from the end longitudinally to a point below the extending arm 82 of the spider 80. Suitable leaf spring members 84 are mounted in vertical extending positions on the external surface of the shoes 66 by means of bolts 85 threading into the shoes 66.

Retaining means 86 are carried by each of the arms 82 at the end thereof, whereby the shoes 66 are supported upon the arms 82 by means of the bearing of the spring members on the upper edges of the arm 82. This provides for resilient mounting of the shoe members upon the spider 80, whereby the shoe members may move radially inwardly and outwardly under the pressure of springs 84 to be expanded or contracted, as desired.

A hollow contact sleeve 90, or any other desired type of contact, is mounted in fixed position above the tube 45, and has an externally enclosing insulating member 92 carried thereabout and maintained in predetermined position with respect to the contact sleeve 90 by means of the lock nut 93 bearing against the lower end of the insulator 92 and threaded onto the contact sleeve. The lower end of the sleeve 90 is provided with a spherically curved portion 91 which is of substantially the same radius as the curved bead 65 of the contact sleeve 45, and which is adapted to

be engaged by the shoes 66 which have a cylindrical surface of a radius substantially equal to the radius of the curved surface 91.

In the operation of the construction shown in Figures 2 to 4, inclusive, rotation of the crank 64 serves to rotate the shaft 50, causing the nut 72 to travel longitudinally of this shaft. This results in downward movement of the member 75 from the position shown in Figure 2, which results in drawing of the upper ends 83 of the shoes 66 downwardly out of engagement with the contact end of the sleeve 90, thereby breaking contact between the contact surface 91 and the contact 40. This downward movement is accommodated by means of the recess portions 67 of the shoes 66 which fit around the beaded portion 65 of the tubular member 45. The traveling nut 72 can move downwardly upon the shaft 50 until the spider 80 rests upon the upper surface of the tubular member 45. Inasmuch as the normal external diameter of the tubular member 45 is substantially less than the beaded portion 65 thereof, or the external diameter of the contact sleeve 90, the shoes will be expanded against the pressure of springs 68 and 83 when in the position shown in Figure 2. Consequently, upon downward movement, the shoes will contract, but cannot contract inwardly beyond the external diameter of the member 80, or the external diameter of the member 45. When the shoes have reached their lowermost position, the upper ends 83 thereof are contracted to a slight extent by reason of the pressure of springs 84, so that upon upward movement into switch closing position, the shoes will be spread radially as they come into engagement with the contact surfaces 91 of the sleeve 90, due to the upwardly and outwardly flaring end portions 83 thereof, so that any slight misalignment of the contact 90 and the tubular member 45 will be accommodated by the swinging movement of the sleeve 75 about traveling nut 72, the sleeve having substantially universal movement about this nut so that as the contact shoes are guided into engagement, the sleeve may rotate about the nut in any desired manner to accommodate any misalignment which may be present. This brings the shoes in uniform contact engagement therewith. Also, by reason of the particular spring mounting disclosed, equalized contact pressure of each of the shoes against the stationary contact is provided, and the wiping action of the shoes across the contact surfaces serves to maintain the surfaces clean and bright.

In Figure 5 I have shown a modified form of spider for supporting the upper end of the contact bars. In this embodiment of the invention, the sleeve 75 is provided with a spider 100, which is formed with a plurality of circumferentially spaced openings 102 adapted to receive the contact shoes 103 corresponding to the contact shoes 66 of Figure 2. The outer peripheral surface of the spider 100 is formed of a polygonal shape corresponding to the number of shoes forming the connector. The shoes are supported against movement with respect to the spider 100 by engagement of a spring member 104 with a notched portion 105 on the outer surface of each of the shoes 103, as shown in more detail in Figure 6. The springs are held in position by rivet members 107, secured to the outer surface of the spider 100 and extending into the openings 102. Suitable web portions 108 are provided in the spider for separating the various openings 102 through which the respective shoes 103 extend. By rea-

son of this arrangement, the shoes 103 are normally pressed inwardly to form a cylindrical surface which is slightly smaller in diameter than the contact surface 91 of the contact 90. Thus, 5 when the shoes are moved upwardly by rotation of the crank 64, the upper ends thereof are spread apart upon engaging the contact surface 91, and the shoes are held in equalized contact pressure engagement with the surface 91 by 10 reason of the springs 104. The cylindrical surface defined by the inner contact surfaces of the shoes and the spherical surface 91 of the contact 90 insure that an unvarying contact area will be provided regardless of the misalignment of the 15 contacts, and also that equalized pressure engagement of each of the shoes will be produced irrespective of any misalignment.

It will be apparent in all embodiments of the invention thus far shown and described, that the 20 connector has limited universal movement with respect to one contact when being moved into engagement with the other contact, so that misalignment of the contacts, within predetermined limits, will not be effective to produce an equalized 25 contact pressure, or to reduce or increase the contact area unnecessarily. Further, by the provision of the contact shoes which are spring pressed into engagement between the contacts, it will be apparent that uniform contact pressure 30 of each shoe against its adjacent contact surface will be maintained, regardless of misalignment of the contact, this being due to the fact that the cooperating surfaces are all formed with the same radius, so that a substantial line contact 35 of uniform contact area will be maintained at all times, and because of the floating arrangement of the contact shoes or connector, equalized contact pressure at all points will be maintained. This is distinctly desirable in circuit controlling means of 40 this type, and the electrical switch connector shown provides for insuring that equalized contact pressure of uniform area will be maintained at all times.

I am aware that various changes may be made 45 in the operating mechanisms of the various embodiments of my invention, and in details of construction of various of the constituent parts thereof. I therefore do not intend to limit myself to the details shown and described, but only 50 in so far as defined by the scope and spirit of the appended claims.

I claim:

1. In combination, a pair of spaced apart contact members each having a convex spherical 55 contact surface, a passage-way through one of said members, a connector having actuating means within said passage-way for moving said connector into and out of engaging contact position, a plurality of individual contact shoes assembled into and making up said connector, said shoes bridging and completing the electric circuit between said spaced contact members when in engaging contact position, and resilient means individual to each individual contact shoe for 60 maintaining equalized and unvarying pressure and contact between contact shoes and said spaced contact members for predetermined positions of misalignment of said spaced contact members.

2. An electrical connector comprising a connecting member comprising a plurality of individual contact shoes, a pair of spaced apart contact members each having a convex spherical contact surface, resilient means individual to each 75 contact shoe for urging said shoes of said con-

necting member into equalized pressure contact with said spaced contact members when in engaged position of said connector with said spaced contact members, and actuating means built internally into one of said spaced contact members for moving said connecting member telescopically over one spaced contact member from open to close position of the connector, while permitting limited universal movement of said connecting member to accommodate for limited 10 misalignment of said spaced contact members.

3. An electric switch comprising, in combination, a pair of spaced apart contact members normally adapted to be in axial alignment but likely to be positioned slightly out of alignment 15 and having convex spherical contact portions; a connector member including a plurality of individual contact shoes arranged to surround both said contact members, each of said contact shoes having contact portions for engaging said convex 20 spherical contact portions, support means cooperating with said contact shoes, and resilient means acting between said support means and said contact shoes for urging said contact shoes into engagement with said convex spherical contact portions of said contact members; said connector member being movable relative to both said contact members for opening and closing a circuit therethrough.

4. An electric switch comprising, in combination, a pair of spaced apart contact members normally adapted to be in axial alignment but likely to be positioned slightly out of alignment and having convex spherical contact portions; a connector member including a plurality of individual contact shoes arranged to surround both said contact members, each of said contact shoes having contact portions for engaging said convex spherical contact portions, support means at each 35 end of said contact shoes, and resilient means individual to each support means and acting between the same and said contact shoes for urging the contact portions thereof into contact engagement with said spherical contact portions of said contact members; said connector member 40 being movable relative to both said contact members to open and close a circuit therethrough.

5. In combination, a pair of spaced apart contact members each having a convex spherical contact surface, a passage-way through one of said members, a connector having actuating means within said passage-way for moving said connector into and out of engaging contact position, a plurality of individual contact shoes with concave cylindrical contact surfaces assembled 55 into and making up said connector, said shoes bridging and completing the electric circuit between said spaced contact members when in engaging contact position, and resilient means individual to each individual contact shoe for maintaining equalized and unvarying pressure and contact between contact shoes and said spaced contact members for predetermined positions of misalignment of said spaced contact members.

6. An electric switch comprising, in combination, a pair of spaced apart normally relatively stationary contact members normally adapted to be in axial alignment but likely to be positioned slightly out of alignment and having convex spherical contact portions; and a connector member movable along the common axis of said contact members and including a plurality of individual contact shoes arranged to surround both said contact members, each contact shoe having a contact surface adjacent each end for en- 70 75

gaging the respective spherical contact portions of said contact members, support means for and movable with said contact shoes, and resilient means individual to each contact shoe and acting between said support means and said contact shoes for urging said contact shoes into engagement with said convex spherical contact portions of said contact members.

7. An electric switch comprising, in combination, a pair of spaced apart normally relatively stationary contact members normally adapted to be in axial alignment but likely to be positioned slightly out of alignment and having convex spherical contact portions; and a connector member movable along the common axis of said contact members and including a plurality of individual contact shoes arranged to surround both said contact members, each contact shoe having a concave cylindrical contact surface adjacent each end for engaging the respective spherical contact portions of said contact members, support means for and movable with said contact shoes, and resilient means acting between said support means and said contact shoes for urging

said contact shoes into engagement with said convex spherical contact portions of said contact members.

8. An electric switch comprising, in combination, a pair of spaced apart normally relatively stationary contact members normally adapted to be in axial alignment but likely to be positioned slightly out of alignment and having convex spherical contact portions; and a connector member movable along the common axis of said contact members and including a plurality of individual contact shoes arranged to surround both said contact members, each contact shoe having a concave cylindrical contact surface adjacent each end for engaging the respective spherical contact portions of said contact members, support means for and movable with said contact shoes, and resilient means individual to each contact shoe and acting between said support means and said contact shoes for urging said contact shoes into engagement with said convex spherical contact portions of said contact members.

CHARLES H. KOEHLER.
